(57) **CLAIM**

We claim the ornamental design for a tripod mount for electronic device, substantially as shown and described.

DESCRIPTION

FIG. 1 is a front left side perspective view of a tripod mount for electronic device in accordance with the present design. FIG. 2 is a rear right side perspective view thereof; FIG. 3 is a top left side perspective view thereof; FIG. 4 is a bottom right side perspective view thereof; FIG. 5 is a right side view thereof; FIG. 6 is a left side view thereof; FIG. 7 is a front view thereof; FIG. 8 is a rear view thereof; FIG. 9 is a top view thereof; FIG. 10 is a bottom view thereof; FIG. 11 is a front left side perspective view of the tripod mount for electronic device with the chucks opened in accordance with the present design. FIG. 12 is a right side view thereof; FIG. 13 is a rear view thereof; FIG. 14 is a front left side perspective view of the tripod mount for electronic device with the chucks opened, upper part and bottom part of the tripod mount pulled extendedly in accordance with the present design. FIG. 15 is a rear right perspective view thereof; FIG. 16 is a right side view thereof; and, FIG. 17 is an exemplary diagram of the use of the tripod mount for electronic device in accordance with the present design, the broken line being shown depicts environmental subject matter only and forms no part of the claimed design.
